UNITED STATES PATENT OFFICE

2,009,813

ELECTRICAL SWITCH

Joseph W. Owens, Schenectady, N. Y., assignor to
General Electric Company, a corporation of
New York

Application October 7, 1933, Serial No. 692,613

7 Claims. (Cl. 200—171)

My invention relates to electrical switches of the type wherein a movable contact member is operable into engagement with predetermined stationary contact members, and has for an object the provision of a simple, inexpensive and reliable switch of this character.

In carrying out my invention in one form thereof, I provide one or more movable contacts each of which is operable into engagement with one or the other of a pair of stationary contacts, a single wiping spring being arranged to support each movable contact and to insure a good wiping action between each movable contact and its associated stationary contacts.

For a more complete understanding of my invention reference should be had to the accompanying drawing, Fig. 1 of which shows an elevation of a switch embodying my invention, while Fig. 2 shows a perspective view of a movable contact member and its associated mounting means.

Referring to the drawing, I have shown my invention in one form as applied to a reversing switch 10 provided with a plurality of stationary contact members, for example the contact members, 12 and 13 secured to a support 14 formed of insulating material as by screws 15 and 16. A movable contact member is provided for each pair of stationary contact members only one, 17, of which is shown. The movable contact member 17 is carried by a support 18 formed of insulating material and mounted on and secured to a rotatable switch shaft 19, said contact member 17 being operable from one circuit controlling position to a second circuit controlling position by turning the shaft 19 as by a handle (not shown)

connected to the shaft. In order to resiliently mount the movable contact and to secure a strong wiping action between the movable contact 17 and its associated stationary contacts 12 and 13, a compression spring 20 is mounted between a spring seat 21 molded integrally with the support 18 and a spring seat 22 formed integrally with the movable contact member 17 as by swaging. As shown, the movable contact member 17 is formed like a block letter C. That is to say, one end 24 of the contact 17 extends inwardly towards the opposite end 25, the two U-shaped ends 24 and 25 being spaced apart from a common side 26.

By removing the compression spring 20 the movable contact member 17 can be removed from the support 18 by rotating the contact member 17 in a clockwise direction until the end 24 passes through an opening or aperture 28 provided in the support 18.

In the operation of my invention, it will be assumed that the switch has been wired in a conventional manner as a reversing switch, the terminal 30 and additional corresponding terminals being connected to the supply source (not shown) and by the flexible shunt 30a to the movable contact member 17, additional shunts being similarly connected to the remaining movable contacts, whilst the motor or load circuit is connected to terminals corresponding to the terminal 31 shown in the drawing. The terminal 31 is connected to the stationary contact member 16 as by conductor 34 and to the stationary contact member 12 by conductor 35. If a three phase circuit is controlled, the two additional pairs of stationary contacts are cross connected to provide reversal of the phase relation on the motor circuit.

It will, of course, be understood that as many circuits as may be desired can be controlled simultaneously by mounting additional contact members on the shaft 19, as by additional apertures 38 provided in the support 18, and by providing corresponding stationary contacts.

In order to change the circuit connections the shaft 19 is rotated in a clockwise direction, the movable contact 17 disengaging itself from the stationary contact 13 to interrupt the circuit. Upon continued movement of the shaft 19 the movable contact member 17 engages the stationary contact 12, the compression spring 20 permitting a certain amount of lost motion between the support 18 and the movable contact 17 so as to provide a good wiping action and a substantial contact pressure.

When the movable contact 17 is in engagement with the stationary contact 13, as shown in Fig. 1, it will be observed that the current-carrying portion 17a is in engagement with the stationary contact 13. However when the circuit is completed through the contact 12 the current-carrying portion 17b is utilized. Consequently, arcing at the contacts occurs at different points on the movable contact member thereby insuring a longer life for the movable contact member.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is,—

1. In a switch, a movable contact member

formed by a C-shaped conductor, a support therefor provided with an aperture, one end of said C-shaped conductor being arranged to extend through said aperture, and a spring between 5 said support and the opposite end of said conductor for maintaining said conductor in engagement with said support.

2. In a switch, a movable contact member formed by a flat conductor having U-shaped 10 end portions and connected together at one side thereof, an apertured support formed of insulating material, one of said U-shaped end portions being adapted to extend through and partially encircle said apertured support, and a 15 compression spring one end of which bears against said support and the opposite end of which bears against said opposite end portion of said conductor for resiliently supporting said contact from said support.

20 3. In a switch provided with a stationary contact member, a substantially C-shaped movable contact member including a center portion interconnecting two end portions, one end portion being operable into engagement with said stationary contact, a support for said contact member engaging said other end portion, and means 25 including a spring located between said end portions and parallel to said center portion for biasing said contact member against said support.

30 4. In a switch provided with stationary contact members, a movable contact member formed by a C-shaped conductor having flattened end portions, one end portion of said conductor being operable into engagement with said stationary contacts, and means including a compression spring for supporting said contact from its other end portion, said spring being located 35 between said end portions and operatively engaging at least one end portion.

40 5. In a switch provided with stationary contact members, a movable contact member formed by a C-shaped conductor, the ends of said conductor extending inwardly from the end por-

tions thereof one end portion of said conductor being operable into engagement with said stationary contacts, a support for said movable contact member provided with an opening for the reception of said other end portion of said movable contact, and a compression spring mounted between said support and said opposite end of 5 said movable contact for resiliently connecting said contact to said support.

6. In a switch provided with stationary contact members, a movable contact member formed by a conductor bent into the form of a block-C, the ends of said conductor extending inwardly from the end portions thereof a predetermined 10 distance, the respective sides of one end portion 15 being selectively operable into engagement with said stationary contacts, an apertured support formed of insulating material for the reception of said other end portion of said movable contact, and a compression spring located between said support and one end of said movable contact for maintaining said movable contact in position on 20 said support and for providing a wiping action 25 between said movable contact and a selected one of said stationary contacts.

7. In a switch provided with stationary contact members, a movable contact member, a rotatable support for said movable contact member, said support being provided with a substantially rectangular opening, said movable contact member being formed by a flat conductor one 30 end of which extends through said opening and partially encircles said support, the other end of which is arcuately formed so that opposite sides 35 of said conductor engage one or the other of said stationary contact members, and a compression spring mounted between said support and one end of said movable contact member for resiliently securing said contact member to said support and for providing a wiping action between 40 said movable contact member and a selected one of said stationary contact members.

JOSEPH W. OWENS.
